UNITED STATES PATENT OFFICE.

HYMAN PRESNICK, OF BROOKLYN, AND SAMUEL YOUNGERMAN, OF NEW YORK, N. Y.

SELF-LOCKING BOTTLE-HOLDER.

1,100,909.

Specification of Letters Patent. Patented June 23, 1914.

Application filed February 21, 1914. Serial No. 820,285.

To all whom it may concern:

Be it known that we, HYMAN PRESNICK and SAMUEL YOUNGERMAN, subjects of the Czar of Russia, and residents, respectively, 5 of Brooklyn, county of Kings, State of New York, and New York city, in the county of New York and State of New York, have invented certain new and useful Improvements in Self-Locking Bottle-Holders, of which the following is a specification.

The invention relates to improvements in self-locking bottle holders arranged in connection with the exterior side of a house-door for the convenient delivery, security, 15 and authorized removal of milk-bottles; and the object of the invention is to provide a holder into which one or more bottles may be readily delivered and automatically locked against displacement while the house-door is 20 closed, and to afford means for conveniently emptying the holder after the door has been opened.

A further object provides means for detachably supporting the holder for the 25 greater convenience in discharging its contents and for its replacement when required for use.

The invention also includes certain details of construction hereinafter set forth.

30 In describing the invention in detail, reference is had to the accompanying drawings, forming a part of this specification, and wherein like characters of reference are used to designate corresponding parts 35 throughout the several views, and in which:

Figure 1 is a ground plan of the device embodying the present invention and shown in connection with a portion of a door and its supporting-frame or jamb; Fig. 2 is a 40 side elevation of the same, shown partially in section, and arranged for containing a single bottle; and Fig. 3 is a side elevation of a part of the holder, showing the position of the locking device thereof during the admission of a bottle.

In the drawings, numeral 1 designates a door-frame or jamb of a house having hinges 2 for supporting a door 3, the latter opening inward of a room and closing a doorway 50 leading to a street or public hall. Upon the jamb 1, exteriorly of the doorway, is fixed a supporting bracket 4, formed with projecting portions 5, provided with slotted perforations 6 for detachably receiving and supporting the bottle-holder 7, which latter consists of a frame-work composed of a series of

spaced rings 8, connected together with vertical cross-bars 9. Round-head pins 10, fixed to the terminal rings of the holder, are adapted to loosely engage the slotted perforations in the bracket 4 and provide convenient means for detachably securing the holder thereto. The holder is provided with opposite open ends constituting an upper admission passage and a lower discharge passage for the bottle, the latter being indicated by the dotted lines 11. The lower discharge passage is adapted to be closed by the plate door 12, hingedly connected at 13 to the frame-work of the holder. A spring latch 14, also fixed to the frame-work, engages a projecting lip on the plate door and maintains the latter in a normally closed position.

To prevent the removal of the holder from its supporting bracket while the house-door is closed, laterally extending lugs 15 are fixed to the lower end of the frame-work and are positioned to engage a stop-bar 16, fixed upon the house-door. The lugs of the 80 holder and the stop-bar of the door project at opposite sides of their supporting points to permit the use of the bottle-holder in both right and left hand door situations. Also to prevent the opening of the plate door 85 12 and the unauthorized discharge of the bottle from the holder while the house-door is closed, a lock-arm 17 is fixed upon the latter and projecting therefrom extends immediately below the holder and arrests any 90 downward movement of the door 12.

Pivotedly mounted to the holder adjacent its upper admission opening, are a plurality of latch-heads 18, carried by U-shaped pins 19, fixed to a series of the vertical cross-bars 9, spaced in pairs embracing the latch-heads, which latter are channel shaped and consist of an inner wall 20 and two side walls 21, between which side walls are guided the upper ends of complementary 100 latch-levers 22, pivotally mounted intermediate their ends to the pairs of vertical cross-bars, which likewise embrace the same. The upper ends of the latch-levers engage the inner walls 20 of the latch-heads, controlling the working movement of the latter, while the movement of the levers themselves in one direction is limited at their lower ends by the extensions 23 thereof engaging the lower ring of the holder. In the 105 delivery of the bottle through the admission opening of the holder, the movement of the

latch mechanism automatically adapts itself to the contour of the bottle, as indicated sequentially in Figs. 3 and 2, respectively, the latter view showing the bottle completely positioned within the holder and locked against withdrawal by the latch members, the latch-heads thereof being positively held in engagement with the contracted portion of the bottle by the latch-levers, which in turn are positioned by the enlarged portion of the bottle.

While the holder is herein shown as containing a single bottle, it will be evident that the same may be vertically elongated for the reception of two or more bottles, all of which will be locked by the latch mechanism engaging the uppermost bottle.

For the removal of the bottles from the holder, and for the detachment of the latter from its supporting bracket, the house-door is required to be opened, which movement carries with it the connected stop-bar 16 and the lock-arm 17. As thus released, the plate door 12 of the holder may readily be opened and the bottles removed through the discharge opening, or the holder together with its contents may be detached from the supporting bracket 4.

It will be obvious that without departing from the principle of the invention the support of the holder may be transposed from the door-frame to the door itself, and the stop-bar and lock-arm fixed upon the door-frame instead of the door, such modification of the arrangement shown being of clear advantage in some situations.

What we claim as our invention and desire to secure by Letters Patent, is:

1. In a bottle-holder attachment for the door and door-frame members of a house, a holder-frame mounted upon one of said house members and provided at its opposite ends with an upper admission passage and a lower discharge passage for the bottle, a closure hingedly connected to said holder and normally closing the discharge passage thereof, a lock arm fixed to the opposite of said house members and adapted when the house door is closed to engage the closure of said holder and intercept its opening movement, and latch mechanism mounted on

the holder-frame adjacent the admission passage thereof whereby a bottle may be admitted through said passage but prevented from being withdrawn therethrough. 55

2. In a bottle-holder attachment for the door and door-frame members of a house, a supporting bracket fixed to said door-frame member, a holder-frame detachably mounted upon said supporting bracket and having at its opposite ends an upper admission passage and a lower discharge passage for the bottle, latch mechanism mounted on the holder adjacent the admission passage thereof whereby a bottle may be admitted through said passage but prevented from being withdrawn therethrough, a closure hingedly connected to said holder and normally closing the discharge passage thereof, laterally projecting lugs fixed to said holder, a stop-bar fixed to said house-door and adapted when the latter is closed to engage said laterally projecting lugs and prevent the detachment of the holder from its supporting bracket, and a lock-arm fixed to said house-door and adapted when the latter is closed to engage the closure of said holder and intercept the opening movement thereof. 70 75

3. The combination with a bottle-holder having at its opposite ends an upper admission passage and a lower discharge passage for the bottle, of a closure for said discharge passage, a series of latch-heads pivotally mounted upon the holder adjacent the admission passage thereof and adapted to 85 yieldingly engage the contracted portion of the bottle, and a series of latch-levers pivotally mounted intermediate their ends upon said holder, the upper end of said levers engaging the latch-heads and the lower ends 90 thereof engaging the enlarged portion of the bottle to effect the positive engagement of the latch-heads with the contracted portion of the bottle.

Signed at New York in the county of New 95 York and State of New York this 19th day of February A. D. 1914.

HYMAN PRESNICK.
SAMUEL YOUNGERMAN.
